DESIGN FOR A MACHINE FOR BREAKING IN SHOES

Samuel Segal, New York, N. Y.

Application July 20, 1932, Serial No. 44,383

Term of patent 3½ years

To all whom it may concern:

Be it known that Samuel Segal, a citizen of the United States, a resident of New York city, county and State of New York has invented a new, original, and ornamental Design for a Machine for Breaking in Shoes, of which the following is a specification; reference being had to the accompanying drawing, forming a part thereof in which

Fig. 1 is a front perspective view in an open position of a machine for breaking in shoes, showing my new design.

Fig. 2 is a view similar to Fig. 1 showing the machine closed.

I claim:

The ornamental design for a machine for breaking in shoes substantially as shown and described.

Signed at New York, in the county of New York and State of New York this 18th day of July, 1932

A. D.

SAMUEL SEGAL.
